TRAY

George V. Skowronski, Neenah, Wis., assignor to American Can Company, New York, N.Y., a corporation of New Jersey

Filed Jan. 17, 1963, Ser. No. 252,090
4 Claims. (Cl. 229—28)

This invention relates to multi-compartment trays. More specifically, the invention relates to tapered trays having a plurality of receptacle portions, particularly suitable for packaging bakery products, which can be readily set up by automatic machinery and shipped in stacked and nest form.

Divided or compartmented trays customarily have vertical sides and a unitary bottom panel coextensive with the area defined by the outer sides of the tray. Such a construction makes it impossible to ship erected divided trays in a stacked or nested form to save space. Even if the sides of the tray are tapered, the full bottom prevents nesting of the carton. Therefore the trays are usually shipped in the form of collapsed blanks to the product packager, who erects or sets up the trays. The setting up of the trays requires either a substantial labor cost or a capital expenditure for tray erection equipment.

Further, the formation of a divided tray from a unitary blank or several blanks is usually quite involved, and the resulting tray often lacks rigidity. When used in the baking industry, it is extremely desirable that the tray be suitable for baking of the product therein. The construction should be such that dough can be deposited in individual pockets or compartments, which are of sufficient rigidity to maintain their shape during expansion of the dough while baking. From the standpoint of ease of erection, rigidity of construction and lower investment cost to the packager, it is desirable to provide a tapered tray construction which has increased rigidity due to separate, reinforced pockets or compartments, and which allows nesting of the tray in a stack of other substantially identical trays.

It is therefore an object of the present invention to provide a divided tray, having tapered compartments or pockets, which is suitable for stacking in a nested condition.

A further object of the present invention is to provide a divided tray suitable for baking wherein the compartments or pockets retain their original shape throughout the baking of products located therein.

Yet another object of the present invention is to provide a divided tray wherein no one compartment has a side wall or bottom common to another compartment and shifting of product from one compartment to another is avoided.

Still another object of the present invention is to provide a divided tray in which the compartments are substantially siftproof to prevent leakage of product located therein.

Another object of the present invention is to provide a tray which readily can be set up on automatic machinery.

Further details, advantages and objects will be apparent from the following specification and appended drawings wherein:

FIGURE 1 is a plan view of a female tray forming blank,

FIGURE 2 is a plan view of a male insert blank,

FIGURE 3 is a fragmentary perspective view of the blank of FIGURE 1 folded for reception of the male insert,

FIGURE 4 is a fragmentary perspective of the blank of FIGURE 2 folded for insertion in the openings of the female blank,

FIGURE 5 is a fragmentary perspective view of the

2

tray according to the present invention with the male blank inserted in the female blank to form compartments or pockets,

FIGURE 6 is a perspective view of the completed tray,

FIGURE 7 is a fragmentary perspective view of the bottom of the completed tray,

FIGURE 8 is a fragmentary perspective view of the completed tray according to the present invention employing a modified pocket forming construction, and

FIGURE 9 is a fragmentary perspective view of the bottom of the modified pocket construction.

Referring to FIGURES 1 and 2, the tray is formed from two blanks, A and B. Blank A, shown in FIGURE 1, is preferably made of paperboard and constitutes the female tray forming portion of the tray. Blank A is divided by score lines 10-12, 14 and 15, and cut lines 13, 16, 17 and 18 into hingedly connected walls, panels and flaps including side walls 30 and 32, center panel 31, glue tabs 33, side panels 34, and end flaps 35. Blank B, shown in FIGURE 2, also is preferably made of paperboard having a heat-sealable coating on the bottom side and constitutes the male pocket forming portion of the tray. Blank B is divided by score lines 50-54 and cut lines 55 into hingedly connected panels and flaps including edge panels 60, connecting panels 61 and 62, bottom panels 63, end panels 64 and side flaps 65.

As is obvious from a comparison of FIGURES 1 and 2, blank B is larger in its longitudinal dimension than blank A. Therefore, in order for the edge panels 60 of blank B to coincide with the side walls 30 of blank A in the completed tray shown in FIGURE 6, it is necessary for blank B to be reduced in size by an accordian type of folding. The actual folding will be described hereinafter with reference to the insertion of blank B into blank A.

The blanks A and B of FIGURES 1 and 2, respectively, are formed into the configurations shown in FIGURES 3 and 4, prior to combining them to form the divided tray. In blank A side panels 34 and attached end flaps 35 are folded downwardly about score lines 15 to the position shown in FIGURE 3. End flaps 35 are positioned at an angle to side panels 34 by folding the end flaps about score lines 14. The initial folding and the subsequent holding in position of the panels and flaps can be readily accomplished by seating the blank over a female die at

least coextensive in area with the outer perimeter of the blank. The openings in the blank correspond to cavities in the die. A male die having projections of substantially the same configuration as the cavities is then lowered on the blank. The projections force the panels 34 and flaps 35 down against the sides of the cavities, which sides have vacuum cups located therein. As the sides and flaps of the blanks contact the sides of the cavities, a vacuum is drawn and the sides and flaps held in place.

Blank B is formed into the configuration shown in FIGURE 4 by depressing bottom panels 63, causing connecting panels 61 and 62 to be drawn closer together, and folding side flaps 65 upwardly. In FIGURE 4 edge panels 60 and connecting panels 61 and 62 lie in the same plane with bottom panels 63 in a separate, parallel plane. End panels 64 are hinged to connecting panels 61 and 62 along score lines 51 and 52 and to bottom panels 63 along score lines 53, and are positioned at an angle to the bottom panels as are side flaps 65 hinged along score lines 54.

The folding of blank B can be performed either independently of insertion into blank A or else in conjunction or simultaneously with the insertion of elements 63-65 in the openings in blank A. When performed as a simultaneous process, blank B having the thermoplastic, heat-sealable coating on the underside is placed in superposed relationship on blank A located on the female die. The free edge of leading edge panel 60 parallel to score line 50 is aligned with the free edge of leading side wall 30 of

blank A. The leading row of pocket forming elements 63-65 are then forced down into the cavities in the female mold by heated plungers to form completed pockets or compartments. Sufficient heat and pressure is applied by the female cavities and the coating plungers to activate the adhesive, thereby sealing the elements of each of the formed blanks together. A second set of pocket forming plungers, either attached to the first set or independent thereof, forms the second row of completed pockets. The process is continued until all of the pockets in the tray are completed. As each set of plungers depresses a row of pocket forming elements, blank B is reduced in its longitudinal dimension by the accordian type of folding action mentioned previously. After depression of the last row of pocket forming elements, the free edge of trailing edge panel 60 coincides with the free edge of trailing side wall 30. Portions of the plungers extend beyond the confines of the cavities to apply heat and pressure to the edge panels 60 and connecting panels 61 and 62 of blank B to adhere them to the underlying side walls 30 and center panel 31 of blank A. FIGURE 5 shows the tray with the pockets or compartments formed and the flange elements of the blanks adhered to each other.

Instead of employing a thermoplastic heat-sealable coating on blank B for adhering the two blanks together, an adhesive may be applied to blank A in the areas indicated by the stippling on FIGURE 1. The adhesive is applied to portions of side walls 30, center panel 31, side panels 34 and end flaps 35 by straight line applicators. After application of the adhesive, blank A is positioned over the female die. Blank B is then placed in superposed relationship on blank A with the leading free edges of the blanks coinciding. The first set of plungers then depresses the pocket forming elements of both blanks simultaneously, forming completed pockets in one step. Any smearing of the adhesive on blank A is immaterial since it is covered by the elements of blank B. The tray is completed by forming the remainder of the completed pockets with additional sets of plungers. The appearance of the tray produced in this manner is the same as shown in FIGURE 5.

The tray is completed by applying adhesive at the underside of glue tabs 33, folding the glue tabs 33 inwardly about score lines 12, infolding side walls 30 and adhered edge panels 60 about score lines 10 and 50, respectively, to a substantially upright position, and then infold-side walls 32 about score lines 11 and adhering the end portions thereof to the adhesive bearing surfaces of glue flaps 33. In the completed tray the edges of the side walls 30 defined by score lines 12 coincide with the end edges of side walls 32. The upstanding side walls, which give greater rigidity to the tray, are inclined at an angle to the center panel to enable a number of the completed trays shown in FIGURE 6 to be stacked in a nested condition. It is obvious that if desired the side walls 32 and glue flaps 33 can be omitted and the tray produced without upstanding side wall portions.

Each individual pocket or compartment has several areas giving greater rigidity. Side flaps 65 not only provide a double thickness where adhered to side panels 34, but the end edges of the side flaps abut the end panels 64 maintaining the shape of the pockets. Referring to FIGURE 7 which shows the bottom of the completed tray, the end flaps 35 overlap the end panels 64 again providing a double wall thickness. The above noted features prevent shifting of the pocket elements and assure substantial sift-

proofness of each pocket. If it is desired to completely siftproof the pockets, they can be sprayed or coated to seal the corners thereof.

Referring next to FIGURE 8, there is shown a modification of the tray according to the present invention. The side flaps 65 instead of being superposed on the inner surface of side panels 34 are adhered to the outer surface of the side panels. FIGURE 8 shows the bottom of the modified tray construction. Changing the location of the side flaps 65 increases the rigidity of the pocket but also increases the complexity of the erection process.

If it is desired to utilize the completed tray for the baking of the contents packaged therein, it is necessary to employ a lining material, such as foil, to prevent burning or scorching of the contents. Both of the blanks A and B employ a layer of foil on the upper surfaces thereof for baking purposes. The use of the board foil combination eliminates the burning or scorching encountered when board alone is used and the uneven baking when foil alone is employed.

The present invention provides a rigid tapered tray which can be stacked for shipment in a nested condition. Employment of reinforced pockets separated from each other prevents product shifting and provides essential sift-proofness for the contents. The tray can readily be rendered completely siftproof if desired and by the employment of a proper lining material be used for baking of the contents packaged therein. Although exemplified with twelve pockets it is understood that the size and shape of the tray may be varied as desired without departing from the scope of this invention.

I claim:

1. A multi-compartment, nestable tray comprising an upper planar panel connecting a plurality of separate tapered cup-like receptacle portions extending downwardly from said upper panel, said upper planar panel spacing each of said receptacle portions from the other receptacle portions, each of said receptacle portions comprising a bottom panel and a pair of opposed end panels hingedly connected to said upper panel and to said bottom panel, said end panels being inclined downwardly and inwardly toward each other; a pair of opposed side flaps hingedly connected to the remaining edges of said bottom panel, said side flaps being inclined downwardly and inwardly toward each other; a pair of opposed side panels transverse to said end panels and hingedly depending from said upper panel, said side panels being inclined downwardly and inwardly toward each other; said side panels and side flaps being adhered together intermediate the bottom panel and the upper panel.

2. The tray of claim 1 having end flaps hingedly connected to said end edges of said side panels and adhered to said end panels.

3. The tray of claim 1 wherein the end edges of said side flaps are in frictional contact with said end panels.

4. The tray of claim 2 wherein the end edges of said side flaps are in frictional contact with said end panels.
